TIME-CONTROLLED MECHANISM.

1,299,340.

Specification of Letters Patent.

Patented Apr. 1, 1919.

Application filed June 15, 1917. Serial No. 174,888.

To all whom it may concern:

Be it known that I, WALTER A. HEINRICH, a citizen of the United States, residing at the city of St. Louis, State of Missouri, have invented a certain new and useful Improvement in Time-Controlled Mechanism, of which the following is a full, clear, and exact description, such as will enable others skilled in the art to which it appertains to make and use the same, reference being had to the accompanying drawings, forming part of this specification.

This invention relates generally to time controlled apparatus, and specifically to certain improvements in time switch controlling and operating mechanisms of the sort periodically operated at predetermined times.

While time controlled mechanisms for controlling switches for electrical circuits are not new, it appears that such devices have not met with the universal acceptance possible for them, particularly by the smaller users, such as the smaller stores, and the like, which employ illuminated show windows or electric signs. I attribute this circumstance primarily to two causes, viz., the high cost of the apparatus heretofore offered, and the complexity of its construction and the resulting inaccuracy.

The purpose of my invention is to provide certain improvements in a time switch mechanism of the sort disclosed in the pending application of Greenstreet and Lumm, Serial Number 171,418, filed May 28, 1917, by virtue of which improvements the flexibility of the device is greatly increased, and its operation and adjustment in certain particulars is considerably simplified. To this purpose, my invention contemplates the provision of an improved day-skipping arrangement, as well as an arrangement for facilitating the starting of the mechanism. These improvements are so simple in the means employed, and so advantageously disposed, as to render their operation and utilization so easy as to make them appeal to the most unskilled prospective buyer.

A further object is to provide an improved day-skipping mechanism whereby the switch operating train may be locked and positively held against operation for a predetermined period of time, and then released at the end of said period of reten-

tion, the said restraining mechanism being operable upon the switch operating mechanism at a point where it is most effective to hold it against operation, and where it affords the least liability of injury to the switch operating mechanism.

A further object is to provide a starting device whereby the time mechanism may be started in operation without necessitating the opening of the casing, even though the mechanism is fixed against bodily movement, as it preferably should be.

Other and further objects and features of my invention will be obvious or pointed out hereinafter, reference being had to the accompanying drawings in which—

Figure 1 is a sectional view through a train of mechanism equipped with my improvements;

Fig. 2 is a detail illustrating the setting dials and coöperating portions;

Fig. 3 is a top view of the mechanisms illustrated in Figs. 1 and 2, certain parts being shown in section.

Referring to these illustrations by means of the reference numerals applied, let it be understood that the numeral 1 designates generally a clock frame portion of a conventional movement, that illustrated being commercially known as the Waterbury movement. It is contemplated that this frame, together with the parts carried thereby, shall be mounted within a conventional clock casing which may be fixed in any suitable disposal. It is to be understood also that this frame carries the complete conventional time train mechanism which is customary in the variety of movement above designated, and the same may have associated with it a clock dial and time indicating hands, all in the usual fashion. In the illustrations only a few parts of the time train are shown, the parts illustrated being for the most part portions of the switch operating train. This comprises in the first place the spring staff 2 carrying the spring wheel 4 and having associated therewith in the conventional relationship the spring 5, which may be wound up in the usual fashion, under the control of the ratchet mechanism 6. Movement may be transmitted from the spring wheel 4 to the switch to be operated by means of a pinion 7, or other suitable gearing. The spring wheel 4 is designed to drive the train com-

prising the spur pinions 8, 9 and 10, the last mentioned of which meshes with pinion 11 conjoined to a governor fan 12.

The periodic operation of the spring wheel 4 may be controlled from the associated time mechanism by means of the arrangement illustrated and described in the Greenstreet and Lumm application above mentioned. It is sufficient in the present instance to state that this mechanism includes the tripping staff 27 and the detent staff 28, both rotatably mounted in the frame. The detent staff 28 carries a counting arm 29 which is adapted to coöperate with the toothed periphery of the spring wheel 4, in which, at predetermined intervals, are formed the deep notches 4^a. The staff 28 also carries the holding arm 32 which is disposed to coöperate with a stud 34 carried on the spur wheel 10. The tripping staff 27 carries the lifting arm 36 which has a forwardly directed portion 36^a crossing below and in coöperation with counting arm 29, and a laterally turned tripping portion 36^b. Mounted on the front of the frame 1 is a setting device including the conjoined pinion 26, setting dial 21 and tripping arms 22. The pinion 26 is designed to be driven from the conventional minute hand sleeve of the time movement in the ratio of 1 to 24, *i. e.*, the pinion 26 is given one rotation upon twenty-four rotations of the minute hand. This rotation of pinion 26 carries dial 21 and the tripping arms 22. The latter are arranged to coöperate with the extremity 36^b of the arm 36, whereby upon rotation of pinion 26 the arm 36 will be raised to lift counting arm 29 and holding arm 32 out of engagement with the switch operating train, for the purpose of permitting the operation of the latter, at the predetermined period. It is obvious that, under normal operation, the switch operating train will be thus released for operation twice in twenty-four hours, it being contemplated that one of these operations will turn on the switch and the other operation will turn it off.

In conjunction with the periodic mechanism just described, and which I do not claim as my invention, I employ a novel day-skipping arrangement which includes in the first place the rotatable and adjustable staff 40 which carries, adjacent its inner extremity a cam 41 and, at its outer extremity a setting handle 42 having associated therewith a pointer 44 and a restraining pin 45. Rotatably mounted on the staff 40 is a Geneva wheel 46 having conjoined thereto a dial 47. This dial is provided with a series of apertures 48, with which the locking pin 45 is designed to coöperate selectively. A spring 49 operates to urge staff 40 inwardly so as to retain locking pin 45 in engagement with any selected one of the apertures 48. Thereby Geneva wheel 46 is

locked for rotation with staff 40. Geneva wheel 46 is adapted to be intermittently rotated from pinion 26 by means of a lug 26^a. In the arrangement shown the Geneva wheel 46 is given one complete rotation upon seven rotations of the pinion 26.

As will be seen by reference to Fig. 1, the cam 41 has a mutilated portion 41^a, the extent of which is equal angularly to the extent of the angle through which the Geneva wheel is rotated by one rotation of the pinion 26. Arranged to coöperate with the periphery of the cam 41 is a locking lever 50 which is pivoted at 51 and held under the tension of a spring 52. The other extremity 80 of the locking lever 50 carries a short rack member 54 which may be swung into mesh with the governor fan pinion 11 upon depression of the other end of the locking lever by the spring 52. The position of the locking lever is controlled by the cam 41 so that, when the extremity of the locking lever 50 is within the mutilated portion 41^a of the cam 41, the rack member 54 will be in mesh with the pinion 11. With the parts 90 in this position, the pinion 11 will be locked against movement, and the entire operating train will be held against operation, even when relieved of the restraint of holding arm 32 and counting arm 29. When the extremity of locking lever 50 is in engagement with the unmutilated perimeter of the cam 41, the rack member 54 will be held out of engagement with the pinion 11, so that the mechanism may be free to operate when relieved of the restraint of holding arm 32 and counting arm 29.

By virtue of the arrangement just described, it will be obvious that the operating mechanism may be restrained against operation throughout a period of an entire twenty-four hours, at the end of which time the mechanism will be left free to operate during the succeeding six days. The day of disability, it will be obvious, may be predetermined by the setting of the cam 41 relative to the Geneva wheel 46, which setting, as above explained, may be made by withdrawing locking pin 45 from engagement with dial 47, and then rotating the staff when thus released, to place it in the desired position. The dial 47 is designed to be disposed in the plane of the dial of the clock, and is suitably subdivided by calibrations so as to indicate the seven days of the week, and thus permit the adjustment of the cam 41 to the proper position. During such time as the Geneva wheel 46 is free from lug 26^a, it is held against rotation by the expansive power of the spring 49 which is held under compression between a collar 40^a carried on the staff, and a portion of the frame 1.

As it is sometimes desirable to stop the time mechanism for various periods, and then to start it again at the end of such pe-

riods, and as it is also desirable that the device shall be fixed in position in conjunction with the switch which it operates and the circuit controlled thereby, I have found it of high importance to provide a device whereby the time mechanism may be started by an unskilled person without requiring the opening of the clock casing. By reference to Fig. 1, it will be understood that 60 designates the escapement wheel of the time movement, which wheel, of course, is actuated in the conventional fashion from the clock spring. The escapement wheel 60 is controlled by a pallet 61 in the conventional fashion, which pallet is pivoted at 62, and its rocking is accomplished through the lever 64 which is swung by the balance wheel. At 65 I have shown a fragmentary section of the clock casing, upon which casing and on the frame 1 is mounted a push rod 66 normally held in an outward position by a spring 67, its outward movement being limited by a stop 68. A head 69 disposed exterior of the casing 65 furnishes a convenient means whereby the rod 66 may be engaged and thrust inwardly. Upon such operation the inner extremity of the rod 66 makes contact with the disengaged arm of the pallet 61, or with the lever 64, and swings the said pallet and the lever in such fashion as to release the escapement wheel 60 and the balance wheel from their stationary positions, and thereby initiate the operation of the time mechanism.

From the foregoing description of the construction and operation of my improvements it is to be seen that they provide very simple attachments to a conventional form of clock movement by virtue of which it is accommodated to the operation of a day-skipping switch-turning mechanism by the addition of very few and simple parts, and that the manipulation and setting of the mechanism is so simple and obvious that it may be successfully undertaken by one having no previous experience or special skill in connection with such devices. It is likewise to be observed that my improvements supply par-

ticularly useful and advantageous features to the device without materially increasing its cost, and tend therefore to render such devices available to possible purchasers of limited means. 50

I am aware that the embodiment of the invention herein described is susceptible of modifications and variations without departing from the scope of the invention as indicated in the following claims. 55

What I claim is;

1. In a time controlled mechanism, the combination with a periodically operated train, of a constantly rotated wheel, a rotatably mounted shaft, a Geneva wheel loosely mounted on said shaft and adapted to be periodically actuated by the constantly rotated wheel, means for locking the Geneva wheel to the shaft, a cam carried by said shaft, a locking member controlled by said cam and adapted to engage a part of the periodically operated train, said cam capable of being arranged in different positions with respect to the Geneva wheel, and means for guiding the operation of the cam positioning means. 60 65 70

2. In a time-controlled mechanism, the combination of a periodically operated train, a constantly rotated wheel, a driven wheel actuated thereby in different ratio, a staff member, a cam member mounted for rotation and to move bodily lengthwise carried by said staff, a locking lever controlled by said cam member and adapted to coöperate with the periodic train to hold it against operation, and means for adjustably securing said staff for movement with said driven wheel, said last mentioned means including a perforated disk coöoperating with the driven wheel, an arm carried by the staff, and a pin carried by said arm, which pin is adapted to enter any one of the perforations in said disk. 75 80 85

In testimony whereof I hereunto affix my signature this 7th day of June, 1917.

WALTER A. HEINRICH
